UNITED STATES PATENT OFFICE

DOROTHY LONG, OF NEW YORK, N. Y., ASSIGNOR TO FRANKLIN SIMON & COMPANY, INC., OF NEW YORK, N. Y., A CORPORATION OF NEW YORK

DESIGN FOR AN ENSEMBLE SUIT

Application filed August 27, 1930. Serial No. 36,804. Term of patent 3½ years.

To all whom it may concern:

Be it known that I, DOROTHY LONG, a citizen of the United States, and a resident of New York city, borough of Manhattan, in the county of New York and State of New York, have invented the new, original, and ornamental Design for Ensemble Suit, of which the following is a specification.

Reference is had to the accompanying drawings, forming a part thereof, wherein—

I claim—

The ornamental design for an ensemble suit substantially as shown and described.

DOROTHY LONG.
